[57] **ABSTRACT**

A generator of micromist and aerosols is disclosed herein, and has a chamber for condensing and stabilizing a mist. The chamber is defined by a first dome which is disposed inside a second dome, so that there is provided an annular cavity between the two domes for housing electrical components. A baffle is provided inside the condensing chamber for limiting the size of particles expelled by the device.

MICROMIST AND AEROSOL GENERATORS

The present invention relates to micromist and aerosol generators.

There are known aerosol generators essentially constituted by a container containing the liquid to be changed into aerosols, a blower or turbine for forming liquid particles or micelles which is controlled by a motor, an atomizing grill, a chamber in which is formed the mist, a starting capacitor for the motor housed within this chamber, and a heating device positioned in the outlet passage for the aerosols.

The invention proposes to improve such generators by increasing their output, prolonging their action, and protecting their fragile components.

According to the invention there is provided a device for producing aerosol mists, comprising a container for liquids to be converted into an aerosol, blowing means for forming a mist of liquid particles from the liquid, an electric motor for driving the blowing means, a housing for the motor, a first chamber for stabilizing the mist and being defined by the space between the housing and a first dome disposed over the housing, and a second dome disposed over the first dome to define a second chamber.

The accompanying drawings illustrate the invention. In such drawings:

FIG. 1 is a perspective view of the apparatus made according to the invention.

FIG. 2 is a schematic view in axial cross section of the micromist aerosol generators.

FIG. 3 is a partial view of a modification of an evacuation device.

There will be described now by way of nonlimiting example, one embodiment of the subject matter of the invention.

The generator is essentially constituted by a container 1 receiving the liquid L to be atomized. The container 1 is surrounded by a synchronous motor M having an atomizing disk 3 mounted at the lower end of the motor shaft Ma.

At the middle part of the atomizing disk 3 is a nozzle whose beak 4a plunges into container 1. On its lower side, tray 3 has flanges 3a forming a ventilator. A flange support 5 for the motor assembly M and its protective housing 7 has feet 5A having sufficient height for bearing into the bottom of container 1 and for forming an air passage P (along the arrows) between container 1 and support 5. The motor group is fixed to container 1 by a system of fasteners with removable springs. On the underside of the motor is recessed a ring 6 having on its side an atomizing grill 6a. The motor assembly is protected by housing 7.

According to a characteristic of the invention, the motor assembly is housed in a first dome or envelope 16 providing a suitable volume between housing 7 and the said first dome 16. This space forms a chamber for stabilizing the mist formed by mixing air and liquid particles. This annular chamber has a selection baffle 16a for stopping liquid particles which have too large a diameter. The chamber C terminates in an outlet, Ca for the micromists and/or aerosols. The first dome is itself surrounded by a second external dome 19 which protects it. An annular space or outer chamber C2 is provided between the two domes 16 and 19 for protecting the inner dome, and for housing a capacitor 15 for the motor M starting which is thereby sheltered from heat, humidity and all contact with the atomized substance. According to the invention, the electrical components of the various other apparatus (motor connection, switches, luminous monitors, circuit interrupters, etc.) are also located in chamber C2 for protection.

This arrangement ensures safety in the handling and operation of the apparatus.

The outlet Ca has a heating device 8 with an outlet 8a suitably shaped to allow maximum dispersion of aerosols and/or micromists. This heating device can be formed by electrical resistances 9 above which is positioned a baffle 20 for stopping particles having too large a diameter. The heating device makes for obtaining very selective aerosols. Such a heating device makes it possible to obtain at will aerosols hav-

ing a size varying from 0.5 to 5 microns, (about 70 to 80 percent) the greatest portion to the micelles developed ranging from 0.5 to 1 micron.

This heating device is also characterized in that when it is not connected to a power supply it mechanically selects cold atomized products, the large drops being systematically eliminated with only super selected aerosols being emitted.

The electrical circuit of heater 8 is such that it cannot operate unless the motor M is put into operation. A control opening 10 allows for checking the operation of the said heater. A control button 11 independent from the control button 12 of motor M allows for the operation of heater 8. There can be added either a timer operating as a circuit interrupter or a fuse 13 between the two electrical circuits of heater 8 and motor M.

The timer makes it possible to fix the duration of operation dependent upon various useful concentrations and the volume of the room to be disinfected. An opening 14 allows for checking the overall operation of the apparatus.

In a modification of the preferred embodiment the heating device 8 in the upper position of the dome can be replaced by a device baffles 21 in its lower part in order to break particles that are too large thereby allowing passage to only the smallest particles and dispersing these in all directions of the space to be treated by means of an accelerator turbine 22 or an electrically or mechanically driven blower operated by motor 23 for example, combined or not with heating.

It is understood that the blower blades 22a can either be disposed on the periphery or on part of the shaft on the turbine, the object clearly being to permeate in a minimum time, the entire volume of the area to be disinfected in order to accelerate the disinfection operation and the treatments concerned with collective aerosol therapy, according to the nature of the substances to be micronized.

In summary, the importance and the advantages of aerosol and/or micromist generators according to the invention:

The appearance of the apparatus is greatly improved; The protection of the electrical equipment and of the condenser is in keeping with required safety standards;

The output of the generators is considerably improved; The generators can be used for maximum disinfection in the absence of people by the production of finely divided thermal aerosols having extended effect. The disinfection of an operating or contagious area can be carried out at night after the departure of the surgical team; the micronized product being able to reach all the germs and pathogenic viruses which may be suspended in the atmosphere;

The generators can also be used to continuously disinfect in the presence of human beings, between two operations, by the production of thermal aerosols and this will eliminate all the microbial flora resulting from the coming and going of the personnel and doctors and convection currents, etc. The generators according to the invention also produce thermal micelles for treatment by collective aerosol therapy in contagious wards and during periods presumed to be favorable for epidemics;

The design of the heater makes it possible to obtain dry mists with a greater output than is possible with existing devices; and

The apparatus is readily transported by means of handle 17.

It goes without saying and as it already appears from what has gone before the invention is in no way limited to those modes of use nor those embodiments of the various components which have been more particularly indicated; on the contrary it encompasses all variations thereof.

What is claimed is:

1. A device for producing mists comprising a container for a liquid to be changed into an aerosol mist, blowing means for forming a mist of liquid particles from liquid withdrawn from said container, an electric motor for driving said blowing means, a protective housing sealably encasing said motor, a first dome disposed over said housing and spaced therefrom to define a mist-stabilizing first annular chamber between said

dome and housing for receiving said mist formed by said blowing means, said first chamber having an aerosol outlet, a second dome disposed over said first dome and spaced therefrom to define a second annular chamber within said device for protecting said first dome, and means for sealing said second dome to said first dome at said aerosol outlet.

2. The invention as set forth in claim 1, further comprising a starting capacitor connected to said electric motor, said capacitor being disposed for protection within said second annular chamber.

3. The invention as set forth in claim 1, further comprising a particle selection baffle means disposed within said first annular chamber for preventing expulsion from the device of particles larger than a predetermined size.

4. The invention as set forth in claim 1, further comprising timing means connected to said device for regulating the duration of emission of liquid particles.

5. The invention as set forth in claim 1, further comprising dispersion means disposed adjacent said aerosol outlet for dispersing the particles of said aerosol mist.

6. A device for producing mists comprising a container for a liquid to be changed into an aerosol mist, blowing means for forming a mist of liquid particles from liquid withdrawn from said container, an electric motor for driving said blowing means, a protective housing surrounding said motor, a first dome disposed over said housing and spaced therefrom to define a mist-stabilizing first annular chamber between said dome and housing for receiving said mist formed by said blowing means, said first chamber having an aerosol outlet, disper-

sion means disposed adjacent said aerosol outlet for dispersing the particles of said aerosol mist, said dispersion means comprising a heating assembly including a baffle mounted on said device and disposed in the path of said particles, and electrical resistance heating means mounted on said baffle for conducting a heating current.

7. A device for producing mists comprising a container for a liquid to be changed into an aerosol mist, blowing means for forming a mist of liquid particles from liquid withdrawn from said container, an electric motor for driving said blowing means, a protective housing surrounding said motor, a first dome disposed over said housing and spaced therefrom to define a mist-stabilizing first annular chamber between said dome and housing for receiving said mist formed by said blowing

10 means, said first chamber having an aerosol outlet, dispersion means disposed adjacent said aerosol outlet for dispersing the particles of said aerosol mist, said dispersion means comprising a heating assembly including a baffle mounted on said device and disposed in the path of said particles, and electrical

15 resistance heating means mounted on said baffle for conducting a heating current.

8. A device for producing mists comprising a container for a liquid to be changed into an aerosol mist, blowing means for forming a mist of liquid particles from liquid withdrawn from said container, an electric motor for driving said blowing

20 means, a protective housing surrounding said motor, a first dome disposed over said housing and spaced therefrom to define a mist-stabilizing first annular chamber between said dome and housing for receiving said mist formed by said blowing

25 means, said first chamber having an aerosol outlet, dispersion means disposed adjacent said aerosol outlet for dispersing the particles of said aerosol mist, said dispersion means comprising a heating assembly including a baffle mounted on said device and disposed in the path of said particles, and electrical

outlet for accelerating said liquid particles outwardly of said device.
